MATCHED HARDWOOD FLOORING

Filed Feb. 23, 1929

FIG. 2.

INVENTOR
PAUL O. MORATZ
BY *Douglas Moon*
ATTORNEY

UNITED STATES PATENT OFFICE

PAUL O. MORATZ, OF BLOOMINGTON, ILLINOIS

MATCHED HARDWOOD FLOORING

Application filed February 23, 1929. Serial No. 342,231.

This invention relates to matched hardwood flooring and more particularly to the formation of a hardwood floor strip that is formed and finished at the mill and when delivered is ready to lay.

It is an object of this invention to so form long thin strips of hardwood such as used in resurfacing old floors in dwellings, or surfacing floors when constructing buildings, 10 that the same may be finished, that is, scraped, filled, stained, varnished, rubbed, polished and waxed, at the mill and when laid in place will present an even surface without cracks or crevices for the collection of moisture, dust 15 or dirt and without projections to catch the mop, broom or brush usually employed in cleaning or polishing.

Such strips are approximately five-sixteenths inches in thickness, two inches in 20 width and vary in length from one to ten feet in length. Hardwood suitable for flooring is expensive and when a hardwood floor is desired it is customary to apply a veneer of suitable wood over a base of less expensive material. The hardwood lends itself to 25 the formation of thin strips for this purpose which are individually secured to the under body of the floor, as wide boards of such veneer would buckle or warp unless secured 30 by nails intermediate their side edges which would be unsightly and cause unevenness in the smooth flat surface desired. It is customary to form hardwood floor strips with interlocking tongue and groove edges and nail 35 to the under floor as each strip is laid so that the nail head is concealed when the next strip is interlocked therewith.

It is a further object of this invention to 40 so form the opposite edges of hardwood floor strips of the usual dimensions that as each strip is laid, the correct position of the nail is readily indicated to the workman, and when so nailed the placing of the next strip in position ready for nailing will completely 45 conceal the nails of the first strip, clear such nails without contact and tie the meeting edges of the upper finished surface of both strips together in such a manner that the upper surfaces lay in the same plane and the 50 meeting of the edges is invisible except when

the graining of the adjacent strips indicate a slight difference.

With these and other objects in view reference is made to the accompanying drawings as illustrating a preferred form of this invention with the understanding that minor detail changes may be made without departing from the scope thereof.

In the drawings:

Figure 1 is a fragmentary perspective view 60 illustrating the ends and top finished surface of two matched floor strips as they would appear when in place.

Figure 2 is a fragmentary view in transverse vertical section illustrating the manner 65 in which each strip is nailed to the under floor or sub-flooring.

As shown, each strip 1 is provided with a groove 2 along one longitudinal edge and a tongue of peculiar construction along the opposite longitudinal edge. Each tongue, as clearly shown in Figure 1, is formed with a shoulder 3 extending at right angles to the upper longitudinal vertical edge 4 of the strip from a point approximately one quarter of 70 the thickness of the strip, with the horizontal surface of the shoulder terminating in a vertical edge 5 of approximately one-half the width of the said horizontal surface or shoulder. From this vertical surface 5 of the shoulder the tongue is curved outwardly and downwardly, with this curved surface 6 undercut to provide a flat under surface 7 joining the lower vertical longitudinal edge 8 at an obtuse angle at a point approximately one eighth 75 of the thickness of the strip. The groove 2 is so formed on the longitudinal edge of each strip opposite the tongue so that the groove will receive the tongue of the next adjoining strip and departs from the upper vertical longitudinal edge 9 of the strip on a curve from a point approximately one quarter the thickness of the strip and continues a sufficient distance inwardly and downwardly to receive the curved part 6 of the tongue and terminates in a flat surface 10, of less width than the sloping flat surface 7 of the tongue and adapted to engage thereunder, said surface 10 terminating in a vertical longitudinal edge 11.

It might be said that the tongue portion is provided with a double notched or off set upper surface, and the groove portion formed with a shoulder adapted to engage snugly in the upper notch and with a wedge adapted to engage under the tongue portion to draw the shoulder into the notch to insure a close fit to insure the positioning of the upper surfaces of the adjoining strips in the same plane.

10 In laying the floor, the points of the nails 12 are engaged in the second notch or off set and are driven at an angle through the tongue and body portions of the strip 1, as shown in Figure 2, into the sub-surfacing 13, and, as 15 shown in said figure, the nail head will be received in said second notch or off set without danger of the workman's hammer defacing either the upper corner of the edge of the finished strip or the tongue portion, also, 20 when laying the next strip, the groove is of such shape as to clear the nail head without danger of engaging it and when the next strip is nailed the wedging engagement of the surfaces 7 and 10 of the tongue and groove 25 respectively, firmly ties the body of the strip above the groove to the upper portion of the tongue to insure a continuous smooth flat surface to the floor.

This second notch or off set not only provides an easy and quick means of indicating to the workman where to drive the nails but also provides a pocket for the reception of the nail heads. If the body of the strip above the notch is brought into engagement with 35 a nail head in the tongue of the adjoining strip an unevenness is caused in the joint between the two strips thereabove. The position of the body below the wedging surface 10 of the groove is cut off so that its longitudinal vertical edge cannot contact the vertical edge under the tongue of the adjacent strip which insures a complete tying action 40 between the wedge and upper surface when the next strip is nailed in place.

45 Matched flooring strips constructed in accordance with this invention have many advantages. They can be laid without driving or blocking, that is, it is not necessary to tap the strip with a hammer to urge it in a horizontal direction against the laid strip. The nails do not have to be driven with a nail set to prevent the finished sharp corner above the tongue being bruised because the nails are driven in an off set, notch or cavity provided 50 therefor. The wedging action between the tongue and groove prevents squeaking of the laid floor. The tongue being curved downward and of relatively large size is not easily broken or injured when the strips are being 55 laid. The clearance for the nail heads provided in the groove of the adjoining strip prevents the body above the groove being raised and the floor to bulge. The grooved edge being drawn by the nail in that strip 60 into a wedging engagement with the tongue

of the laid strip presents a floor surface free from grooves, cracks or creases at the joints to collect moisture, dust or dirt, as the wedging action produces a tight joint between the upper edges of the strips and firmly holds 70 these edges of the strips in place against future rising or springing. These many advantages of this invention allow the floor strips to be completely finished at the factory and the floors so made are ready for use 75 as soon as laid.

What I claim is:

1. A matched hardwood flooring comprising a plurality of hardwood floor strips, each strip provided with an outstanding tongue 80 along one longitudinal edge and a groove along the opposite edge adapted to receive the tongue of the next adjacent strip, said tongue having a longitudinal right angular off set adapted to receive the head of a nail 85 driven through the tongue and body of the strip and having an undercut portion sloping toward the underside of the strip to the longitudinal vertical edge, and said groove curved to clear the nail heads received within the offset, and formed with a correspondingly shaped lower portion of less length than the undercut of the tongue and adapted to engage thereunder and tie upper edges of the adjacent strip together in the same plane. 90

2. A flooring strip provided with tongue projecting along one longitudinal edge having a flat surface at right angles to the edge terminating in a longitudinal right angular notch adapted to receive the head of a nail 100 driven therethrough, said tongue having an undercut portion forming a flat surface sloping towards the underside of the strip and terminating at the longitudinal edge above the lower corner thereof, and a groove entering the opposite longitudinal edge, forming a shoulder adapted to engage the said flat surface and edge of the tongue upon the next adjacent strip and receive said tongue and clear the heads of nails driven through said 105 notch, and having a flat surface at the bottom of the groove corresponding to the flat undercut surface on the tongue and adapted to engage under the next adjacent tongue and produce a wedging connection therewith to tie the upper corner of the two strips together with their upper surface in the same plane. 110
